UNITED STATES PATENT OFFICE.

HENRY O. PEABODY, OF BOSTON, MASSACHUSETTS.

DESIGN FOR A CHIN-REST FOR VIOLINS.

SPECIFICATION forming part of Design No. 27,242, dated June 22, 1897.

Application filed May 7, 1897. Serial No. 635,596. Term of patent 14 years.

To all whom it may concern:

Be it known that I, HENRY O. PEABODY, of Boston, in the county of Suffolk and State of Massachusetts, have invented and produced 5 a new and original Design for Chin-Rests for Violins, of which the following, taken in connection with the accompanying drawings, is a specification, reference being had to the accompanying drawings, forming part thereof.

10 Figure 1 of the drawings is a plan view of a chin-rest, showing my new design. Fig. 2 is an elevation of the same, looking toward the top of Fig. 1. Fig. 3 is an elevation looking in the opposite direction. Fig. 4 is a sectional elevation, the cutting-plane being on line xx on Fig. 1 and looking toward the right of said figure; and Fig. 5 is an inverted plan.

15 As shown in the drawings, the leading or material feature of my design consists of a thin curved plate a , having an outline in plan approximating an oval or egg shape and provided on one edge with a downwardly-projecting rib b of considerable thickness extending from the most-pointed end of said 20 plate about two-thirds, more or less, of the length of said plate toward its other end and having a flat under surface to bear upon the

25 violin, that portion a' of said plate which extends beyond the end of said rib being curved upward to a considerably-greater height than any other portion thereof, and the whole of 30 said upper surface of said plate being transversely inclined to the plane of the flat under surface of the rib b , as shown in Fig. 4. The outer face of the rib b has formed therein the 35 two holes $c c$ to receive turnbuckles for securing it to the violin, and dd are bosses upon the inner face of the rib b to give greater thickness of stock to receive said turnbuckles, as indicated in Fig. 5.

40 Having described my invention, what I claim as new, and desire to secure by Letters Patent, is—

45 The design for a chin-rest for violins as herein shown and described.

In testimony whereof I have signed my name to this specification, in the presence of two subscribing witnesses, on this 5th day of May, A. D. 1897.

HENRY O. PEABODY.
